CLOTHES HANGER

Catherine B. Creveling and Elmer V. Pennell,
Patterson, N. Y.

Application March 3, 1950, Serial No. 147,368

2 Claims. (Cl. 211—113)

1

The invention herein disclosed relates to garment hangers, and objects of the invention are to provide a simple, inexpensive form of hanger which will support garments such as trousers, skirts and the like, without slipping, regardless of the character or thickness of the material, and which will permit of the clothes being quickly and easily engaged and removed.

Further objects of the invention are to provide a hanger consisting of but few parts and which will take up but small space and yet may be utilized to support a suitable quantity of clothing.

Other objects of the invention are to provide a garment hanger in the form of a unit which may be combined with other similar units to hang practically any quantity of clothing.

Additional objects are to provide a hanger of light but strong construction, so designed that it will be able to carry heavy loads of clothing without injury.

Other desirable objects and the novel features of construction, combination and relation of parts through which all purposes of the invention are attained, are set forth or will appear in the course of the following specification.

The drawing accompanying and forming part of the specification illustrates a present practical embodiment of the invention, but structure may be modified and changed as regards the immediate illustration, all within the true intent and broad scope of the invention as hereinafter defined and claimed.

Fig. 1 in the drawing is a front elevation of one of the hangers with portions shown in section;

Fig. 2 is an end view of the same;

Fig. 3 is a vertical cross sectional view of the hanger on substantially the plane of line 3—3 of Fig. 1, showing how a garment may be looped over one of the supporting rods and the latter then caught in the inclined wedge-ways provided for the same;

Fig. 4 is a horizontal sectional view as on substantially the plane of line 4—4 of Fig. 1;

Fig. 5 is a front elevation showing two of the hanger units hooked together and suspended one from the other, parts shown broken and in section;

Fig. 6 is an enlarged broken sectional detail on substantially the plane of line 6—6 of Fig. 5;

Fig. 7 is a broken part sectional detail showing how garments may be hung at opposite sides of the cross bars.

In its simplest form, the hanger comprises 55

2

a bar or board 10 of wood or other suitable material having plates 11 secured over opposite ends of the same by suitable fastenings such as screws 12 and rods 13 supported by said end plates in position to clamp garments against the opposite faces of the supporting bar.

The supporting and clamping rods 13, over which garments such as indicated at 14, may be looped or draped, may be cylindrical wooden dowels cut to length to fit loosely in between the end plates 11.

To confine these dowels or rods against opposite faces of the supporting bars, plates 11 are shown as having inwardly directed and downwardly inclined edge flanges 15 spaced from the supporting bar at the top a greater distance than the diameter of the dowels and sloped inwardly to a distance of less than this diameter at the bottom, approximately as shown in Fig. 7.

This construction, as shown at the bottom in Fig. 3, provides wedgeways which will support the rods, whether empty or holding garments or other articles looped over the same, and this downward and inward wedging action is automatic and self-adjusting to grip any thickness or character of material. And while holding the material or garment the more firmly as pull is applied thereto, the hold can be easily broken by simply lifting the rod free entirely, out of its inclined end sockets, or just lifting it sufficiently to relieve the grip on the clothing.

These rods are readily replaceable if lost or broken, and since the rod as it lowers itself in the guideways automatically braces itself against the face of the supporting bar, these rods, even of small diameter, can support heavy loads without breaking.

To carry as many garments in one unit as possible, a plurality of the bars may be put together, suspended one from the other, as shown in Figs. 1, 2 and 3, as by means of suspension wires 16 arranged with spacing sleeves 17 on the wires between adjoining bars. Two, three, or any number of the bars may be combined in a single unit, but rather than build up a large size rack, it has been found best to make the hangers in something like three-bar units and then combine these units by suspending them one from another, as shown in Fig. 5.

The latter view shows how the top bar of each unit may be equipped near the ends with hooks 18 to engage over loops 19, dependent from the bottom bar of an upper unit.

Loops 19 are shown formed as continuations

of the spacing and suspension wires 16, held spaced beneath the bottom bar by spacer sleeves 20.

The top bar of each unit also preferably is equipped with a suspension hook 21, and to get these hooks out of the way when a unit is hung from another unit, these hooks are shown as swiveled at 22 and as having straight end portions 23 which can be pushed down into sockets 24 in the top bar, to be out of the way and to stand clear of the wedge rods 13, all as shown at the bottom hanger in Fig. 5.

While capable of carrying garments at both sides, the hangers are relatively thin so as not to take up much room in a closet. This is particularly so, as pointed out above, since supporting rods of quite small diameter may be used for hanging the clothes. Since the pressure of these rods is downward and inward against opposite sides of the supporting bars, the end plates 11 and the fastenings 12 therefor can be relatively light. The bars or boards 10 may be of light wood, plastic, metal or other material, since the pressure is balanced against them on opposite sides by the rods and the rods act as reinforcements for the bars.

The structure is simple to manufacture, requires only a few parts, and it is light, strong and very practical.

What is claimed is:

1. A garment hanger comprising vertically spaced, connected parallel bars having inclined guideways at the opposite ends thereof, each guideway being open at the top and sloped downwardly and inwardly toward the bottom of the bars, garment supporting rods loosely held in said inclined guideways by the bars and means

for suspending said multiple bar hanger as a single unit, said unit having suspension hooks and loops at the top and bottom bars of the same cooperative to effect the suspension of one hanger unit from another.

5 2. A garment hanger comprising parallel bars arranged in spaced relation one above the other, suspension wires extending through end portions of the bars, spacer sleeves on said suspension wires between the bars, plates with flanges providing guideways mounted on opposite ends of said bars and garment clamping rods slidably mounted in said guideways to wedge against said bars, said suspension wires extending below the bottom bar and formed with loop portions, and hooks on the top bar in line with said loop portions for enabling the suspension of one multiple bar unit from another.
